UNITED STATES PATENT OFFICE.

FRANK C. ANDERSON, OF CINCINNATI, OHIO.

SWITCH STAND.

Application filed November 6, 1922. Serial No. 599,354.

To all whom it may concern:

Be it known that I, FRANK C. ANDERSON, a citizen of the United States, residing at Cincinnati, in the county of Hamilton and 5 State of Ohio, have invented certain new and useful Improvements in Switch Stands, of which the following is a specification.

My invention relates to ground-lever parallel-throw switch-stands in general; and 10 in certain respects it relates more particularly to the switch-stand disclosed and claimed in my Patent No. 1,427,082, dated August 29, 1922.

Its object is to simplify the construction 15 and operation of switch-stands of this character, and to effect economy in their maintenance; especially to provide means for quick repair in conjunction with use of a breakable switch-throwing crank for protecting the mechanism of the switch-stand and the switch in case the switch is run 20 through in the wrong direction, which breakable cranks are well known in the art, and to insure the making of this repair correctly, even by an unskilled workman, thus 25 avoiding the danger of disconnection of such a breakable-crank mechanism incorrectly or incompletely connected. Other objects, peculiar to the present invention, as well as in 30 common with those of the mentioned patent, will appear in the course of the ensuing description.

I attain these objects by the device illustrated, for example, in the accompanying 35 drawing, in which—

Figure 1 is a sectional plan view of the switch-stand, the section being through the casing on the plane of the line 1—1 of Fig. 2;

Fig. 2 is a sectional front elevation, the 40 partial vertical section through the base and casing being on the plane of the line 2—2 of Fig. 1;

Fig. 3 is a vertical front-to-rear section on the plane of the line 3—3 of Fig. 1;

Fig. 4 is a detail perspective view of the 45 crank-holding bracket;

Fig. 5 is a similar view of the rack or slide; and

Fig. 6 is a similar view of the handle- 50 lever-crank bearing-block.

The base of the stand comprises the middle part 1, feet 2 at opposite ends, bolt sockets 3, front shaft bearing 4, segmental rear extension 5 with bearing opening 6, de-

pression 7 between the bearing 4 and opening 6, and pedestals 8 at opposite ends of this depression 7; this combination being similar to that of the previous invention above referred to. A single guide-bar 9, of circular cross-section, has its ends in transverse openings of the pedestals 8, thus extending across the base above the rear part of the depression 7, up some distance from the top of the flat middle part 1 of the base.

The casing, like that of the mentioned previous invention, comprises the front shaft bearing 10, rear extension with target-shaft-bearing opening 11, and bolt ears 12 registering with the bolt sockets 3 of the base, and being held down on the base by bolts 13 through ears on the base and casing at opposite sides of the front bearings 4 and 10, and bolts 13' in the base sockets 3 and up through the ears 12.

The handle-lever 14 has at its free end the 75 weight-handle 15, and at its other end, preferably forged integral with this lever, the crank-shaft 16, lying in the bearings 4 and 10 and extending back over the front part of the depression 7. This lever bears on one 80 lever-rest 14' or the other, as thrown from side to side, which rests will be understood to be fastened to the ties or head blocks of the switch, not shown. This handle-lever arrangement is the same as that of the previous 85 invention.

The handle-lever crank 17 comprises a hub 18 fitting on the inner end of the shaft 16 and held thereon by a key-pin 17' and a transverse pin 17'', and near its free end 90 has a front-to-rear bearing opening 19 radially alined with the lever 14.

The rack or slide member 20 comprises an upright back 21 and horizontal top 22 extending back from the top of the back 21, 95 forward guides 23, parallel to each other at opposite edges of the back 21, and top guides 24 parallel to each other from front to rear at opposite edges of the top 22. Also, it comprises the lower rear side walls offset 100 laterally from the guides 23 and 24 at opposite sides of the member, with holes 25 through them in transverse alinement, which fit slidingly on the guide bar 9; the lateral offsetting of these walls spacing the bearings 105 thus formed in the holes 25 farther apart and better resisting sidewise tilting or binding of the member 20 as it slides along the

bar 9. All of these described parts of this member preferably are integral, in the form of a steel casting; and the inner sides of the guides 23 and 24 preferably are finished 5 smooth and straight, as also is the front surface of the back 21 between the guides 23. The bearing block 26 slides up and down between these front guides 23, with its sides and rear edges finished smooth and straight 10 to bear against the finished guide and back surfaces; and it has, projecting from its front surface, at the middle thereof, the bearing lug 27 fitting snugly in the bearing opening 19 of the handle-lever crank 17, 15 preferably being turned smooth for accurately fitting in this opening.

The target-shaft 28 will be understood to be of suitable design in its upper part, not shown, to support a target or lamp or other 20 means at any required height, as usual in switch-stands. The intermediate crank 29 has the hub 30 with the target-shaft through it, and near its free end this crank has the bearing lug 31 projecting down, as 25 closed and claimed in my prior patent before mentioned. In that patent, this lug is surrounded by a bearing block that slides between top guides or jaws of the rack or slide; but herein the lug 31 bears directly 30 on the inner sides of the top guides 24, fitting snugly between them, on a radius suited to the throw of the rack member or slide 20. It will be understood that the bearing block may be used herein by spacing the 35 guides farther apart as in said prior patent, or by reducing the diameter of the lug 31, as is shown, for example, in my Patent No. 1,413,152, issued April 18, 1922. Such an intermediate-crank lug was originally claimed 40 by me in my co-pending application Serial No. 477,228, filed June 13, 1921; and may be used with or without a bearing block, as desired. In the present invention, the top 45 guides 24 have the same spacing as the front vertical guides 23, and both pairs of guides may be finished with the same cutter, economizing in the manufacture.

The lower end part of the hub 30 of the intermediate crank 29 extends down into and 50 bears in the base opening 6, while the target-shaft extends up through and bears in the opening 11 of the casing. A flange 32 on the hub 30 bears on the base around the opening 6, supporting the crank 29 at the 55 proper height to work easily with the rack or slide 20 by virtue of its lug 31 fitting between the top guides 24. Pins 33 fix the target-shaft in the crank hub 30. The bottom of the crank hub 30 has a transverse 60 groove; and the direct switch-throwing crank 34 has its hub fitting up in the opening 6, with clutch-teeth 35 engaged in the groove, while the lower end part of the target-shaft 28 extends through the smooth 65 central bore of this hub of the crank 34 and

projects some distance below the bottom thereof. This crank 34 comprises, as here shown, two opposite radial arms 36 integral with its hub and having openings up and down through them near their outer ends. 70 Near their junctions with the hub, these arms 36 have parts 36' of reduced cross-section. The switch-connecting rod 37, as here shown, simply lies on the top of one of the arms 36, with a pin 38 fitting in the arm opening; 75 the pin being retained down in operative position by a base projection 39 having an opening 40 for inserting the pin, as fully set forth and claimed in my Patent No. 1,389,730 issued September 6, 1921. 80

At its extreme rear, the base has a rear ledge 41; and the bracket 42 comprises a top forward extension 43 fitting on top of this ledge 41, a downwardly and forwardly curved body 44, and a fork 45 at the lower 85 front end of this body 44, having its members straddling the part of the target-shaft 28 that projects below the crank 34, with the bottom of the crank hub bearing on the tops of these fork members, whereby the 90 crank 34 is held up in operative engagement, by means of its teeth 35, with the hub 30 of the intermediate crank 29. The bracket 42 is held to the base rear ledge 41 by screws 46 passed down through openings in 95 the top extension 43 of the bracket, into the ledge 41, at opposite sides of the median front-to-rear line of the bracket; and in the vertical plane of this line the bracket has the front or inside rib 47 from its top extension 43 down to its fork 45, and the upper outside rib 48 and the lower outside rib 49 at the junctions of the body 44 with the extension 43 and the fork 45, respectively. The rear edge of the ledge 41 has a notch 100 50 at its middle, admitting the upper part of the inside rib 47 and allowing the side parts of the body 44 to bear against the edge of this ledge 41.

When the switch is run through in the 110 wrong direction, a very frequent occurrence, especially in yards, the arm 36 of the crank 34 that is connected to the switch by the rod 37 will be broken at its reduced part 36', thus avoiding the breakage of the switch 115 rails or of a more expensive and inaccessible part of the switch-stand, as is well known in the art. The switch-stand then is repaired by removing the crank 34 downward from the shaft 28, turning it 180° and replacing it on the shaft 28, connecting the opposite arm 36 to the rod 37; or, if the crank has had this opposite arm broken off at a previous occurrence of the kind, a new 120 crank 34 is substituted. The crank is very 125 readily disconnected from and connected to the rod 37 by virtue of the simple pin held by the base projection 39 and admitted through the opening 40, according to my previous invention just before referred to. 130

Where a breakable pin, rather than a breakable crank, is used, as exemplified in the patent on that invention, the connection of the crank 34 to its shaft 28 may be practically permanent, as shown in that patent. But many users prefer the breakable crank, which requires removal and replacement, as just described, and which, while very dependable if properly connected to the switch-
5 stand mechanism when the repair is made, is liable, with the various means of holding it in connection heretofore in use, to be incompletely connected so that it becomes detached under operating strain, putting the switch out of order and endangering traffic
10 thereover. For instance, where a nut is screwed on the lower end of the shaft 28 under the crank 34, it is very difficult for the workman to reach, and the work must be done largely without actually seeing the
15 connection being made; and under these disadvantages the nut may be screwed on only to a slight degree, not bringing the teeth 35 into adequate mesh, so that they are broken, or else the nut will become unscrewed
20 and allow the crank 34 to drop off, out of mesh with the mechanism in the stand.

With my present invention, the crank 34 is removed by first removing the bracket 42, which is permitted by removal of the screws 46, out within easy reach of and in full view of the workman. With these screws out, the bracket simply is lifted away, allowing the crank 34 to drop off, and then when this crank is replaced in reverse position, or a new crank is substituted, as before described, the bracket 42 is replaced with its fork 45 under the crank 34 and straddling the shaft 28, and its top extension 43 on the ledge 41, and the screws 46 replaced, completing the repair very quickly. The fork 45 engaging under the crank 34 and straddling the shaft 28 cannot readily be seen by the workman; but he cannot pass the extension 43 over the ledge 41, if the fork does straddle the shaft 28, without bringing the crank 34 up with its teeth 35 in complete mesh with the intermediate crank 29. And he cannot replace the screws 46 unless the fork 45 does straddle the shaft 28. Moreover, the operating strains are powerless to materially loosen the screws 46; and even some loosening of these screws will not permit the crank 34 to drop enough to impair its connection with the intermediate crank 29. And if there is any excessive loosening of this bracket 42, it is readily seen by the trackman who inspects the track and switches; whereas any connection, such as the nut above instanced, in under the stand, is extremely liable to go unnoticed by the trackman if it becomes loose or detached as before described. Thus, my improved crank-retaining means has its essential connection in full view for inspection
55
60
65

and repairs, and its engagement with the parts retained by it, though out of view or convenient reach, is positively controlled by the essential connection in full view, both as regards correct assemblage and as regards 70 maintenance of this assemblage. It in no way interferes with the operation of the switch-throwing crank 34, which, in all practical stands, always stops with its arm about 45° from the front-to-rear region in 75 which my improved retaining means is located, as clearly seen in Fig. 1.

The bearing block 26 in the vertical guides of the rack or slide 20, with an elongated vertical bearing therein and held vertical by 80 its connection with the lever-crank 17, serves to prevent the slide or rack 20 from tilting forwardly or rearwardly, although traveling on a single round bar 9, instead of on two such bars as in my prior Patent No. 1,427,082, 85 before referred to; and in addition, this block affords a more extended, longer-wearing and more easily working connection between the lever-crank 17 and the rack 20, than the round projection sliding in the rack 90 in that previous invention. Thus the construction is simplified and the cost of manufacture reduced by eliminating one of the bars 9, however without permitting tilting of the rack, which would cause it to bind 95 upon or become partially disconnected from the adjacent parts; while the increased bearing surface improves the working of the mechanism.

Modifications may occur, and while I have 100 shown and described specifically certain preferred details, I do not wish to be understood as being limited thereto, but what I claim as new and desire to secure by Letters Patent is:

1. In a switch-stand, supporting means, a rack element and a lever operatively mounted on said means, a crank coaxially connected with said lever in radial alignment therewith and operatively related to said rack, 110 an intermediate crank operatively related to said rack element and having a bearing in said supporting means, a direct-switch-throwing crank coaxially connected with said intermediate crank and offset downwardly therefrom, and a bracket on said supporting means holding said switch-throwing crank in operative connection with said intermediate crank.

2. In a switch-stand, a crank on an upright axis, a direct-switch-throwing crank comprising an arm and a hub integrally connected, said hub operatively engaging coaxially with said first crank, a shaft fitting loosely in said hub and fitting in said first mentioned crank, a support for said cranks, a bracket on said support holding said cranks in operative engagement, a lever, and an operative connection from said lever to said cranks.

3. In a switch-stand, mechanism comprising a lever and a crank coaxially connected in radial alinement, a rack above said crank having a vertical guideway, said crank comprising a pivoted block sliding in said guideway, an intermediate crank operatively related to said rack thereabove, a direct-switch-throwing crank coaxially connected with said intermediate crank, and means operatively supporting said mechanism.
4. In a switch-stand, mechanism comprising a lever and a crank coaxially connected in radial alinement, a rack above said crank having a vertical guideway, said crank comprising a pivoted block sliding in said guideway, an intermediate crank operatively related to said rack thereabove a direct-switch-throwing crank coaxially connected with said intermediate crank, means operatively supporting said mechanism, and a bracket on said supporting means holding said switch-throwing crank in operative connection with said intermediate crank.
5. In a switch-stand, a base, a lever and a crank coaxially connected and mounted on said base, a casing enclosing said crank, mechanism enclosed in said casing, comprising a rack having a vertical guideway, said crank comprising a pivoted block sliding in said guideway, a single guiding means, past the end of said crank and block, and means on said rack slidably embracing said guiding means, and means extending outside said casing to operatively connect said rack to a switch.
6. In a switch-stand, in combination with a casing, and a lever and a switch-connecting rod outside said casing, three cranks, one inside said casing and connected to said lever and another outside said casing and connected to said rod, and the third crank inside said casing and connected to this other crank coaxially to turn therewith, a horizontally sliding element inside said casing, and an element sliding vertically on said horizontally sliding element, operatively connected to the lever-connected crank, these sliding elements operatively connecting this lever-connected crank to said third crank.
7. In a switch-stand, mechanism comprising a rack, means connecting said rack to a switch, and rotary means for sliding said rack, a single bearing bar extending along past one end of the rotary means, said rotary means comprising an element rectilinearly guided on said rack, and means on said rack retentively bearing on said bar, whereby said rack is guided on said bar and overhangs therefrom for engagement with said element of said rotary means.
8. In a switch-stand, a rack member comprising an upper part with parallel jaws on its top, downward extensions near opposite ends of said upper part to receive part of a crank between said extensions, and other

downward extensions, joined to the respective first mentioned downward extensions and each having only a single circular opening to receive a single round guiding means through the two openings of the two extensions. 70

9. In a switch-stand, a support, a crank below said support, mechanism on said support to which said crank is connected for removal downwardly, and a bracket removably secured to said support, holding said crank up in connection with said mechanism. 75

10. In a switch-stand, a support, a crank below said support, mechanism on said support to which said crank is connected for removal downwardly and by which said crank is turned through a switch-throwing angle, and a bracket removably secured to said support outside the area defined by said angle, holding said crank up in connection 85 with said mechanism.

11. In a switch-stand, a support, a crank below said support, mechanism on said support to which said crank is connected for removal downwardly, swinging said crank in switch-throwing direction, and a bracket removably secured to said support and extending to said crank substantially parallel with the switch-throwing direction and holding said crank up in connection with said mechanism. 95

12. In a switch-stand, a support, a crank below said support, mechanism on said support to which said crank is connected for removal downwardly and comprising a shaft 100 extending past the bottom of said crank, and a bracket secured to said support, comprising a fork straddling said shaft and holding said crank up in connection with said mechanism.

13. In a switch-stand, a support, a crank below said support, having oppositely extending arms, mechanism on said support to which said crank is connected for removal downwardly, and a bracket removably secured to said support and extending to said crank between the areas defined by the switch-throwing angles of the opposite crank arms, holding said crank up in connection with said mechanism. 110

14. In a switch-stand, a support, a crank below said support, mechanism on said support to which said crank is connected for removal downwardly, swinging said crank through a switch-throwing angle substantially symmetrical to a radius parallel with the track to which the switch-stand is applied, and a bracket removably secured to said support and extending to said crank substantially at right angles to the track, 120 holding said crank up in connection with said mechanism.

15. In a switch-stand, a support, a crank below said support, mechanism on said support to which said crank is connected for re- 130

moval downwardly, and a bracket removably secured to said support, out from under said support, and extending under said support and holding said crank up in connection with said mechanism.

5 16. In a switch-stand, a support, a ledge on said support, a crank below said support, mechanism on said support to which said crank is connected for removal downwardly, 10 and a bracket comprising a top extension removably secured on top of said ledge, said bracket extending under said support and holding said crank up in connection with said mechanism.

15 17. In a switch-stand, a support, a ledge on said support, a crank below said support, mechanism on said support to which said crank is connected for removal downwardly and comprising a shaft extending past the 20 bottom of said crank, and a bracket comprising a top extension removably secured on top of said ledge, said bracket extending under said support and comprising a fork straddling said shaft and holding said crank up in connection with said mechanism.

25 18. In a switch-stand, a support, a crank below said support, mechanism on said support to which said crank is connected for removal downwardly and comprising a shaft extending past the bottom of said crank, 30 and a bracket secured to said support out from under the support and extending under said support and comprising a fork

straddling said shaft and holding said crank up in connection with said mechanism.

35

19. In a switch-stand, a support, a ledge on said support, a crank below said support, mechanism on said support comprising rotary means with clutching means, said crank having clutching means operatively engaging with the clutching means of said mechanism and being disengageable by movement downwardly therefrom, said mechanism comprising a shaft extending through said crank and projecting therebelow, a 40 bracket comprising a top extension removably secured on top of said ledge, and a fork comprised in said bracket, straddling said shaft below said crank and bearing up against said crank to hold said crank in 45 clutching engagement with said clutching means of said mechanism.

50

20. In a switch-stand comprising operating mechanism, a breakable crank under said stand, and a bracket supporting said crank in operative engagement with said mechanism by engagement with said crank under said switch-stand, said bracket extending out from under said switch-stand and being attached to said stand upon a 55 readily accessible and readily visible part of said stand, for ready detachment and reattachment in repairing said stand after breakage of said crank.
